SNARE DRUM

Application filed April 2, 1929. Serial No. 351,946.

This invention relates to sound propagating diaphragms.

It is among the objects of the present invention to provide a novel and improved 5 diaphragm supporting structure and method of securing the diaphragm to the supporting structure.

It is a further object of the present invention to provide an improved method of and 10 means for securing and stretching flexible diaphragms.

A further object of the present invention is to provide a novel and improved method of 15 and means for securing snares in combination with a sound propagating diaphragm.

Other important objects of the invention include the combination and interrelation 20 of parts whereby the whole forms a simple, efficient and economical structure readily assembled and admirably adapted to meet the demands of economic manufacture.

Numerous other objects and features of the 25 present invention will be apparent from a consideration of the following specification taken in conjunction with the accompanying drawings, in which

Figure 1 is a perspective view of one embodiment of the present invention;

Fig. 2 is a transverse section through that 30 form of the invention illustrated in Fig. 1, showing one step in the present method;

Fig. 3 is a fragmentary sectional view showing the invention after the steps of the 35 method have been completed, and

Fig. 4 is a similar view illustrating the method of securing the snares and taken on lines 4—4 of Fig. 2.

Referring more particularly to the drawings, the invention is herein disclosed in an 40 embodiment particularly adapted for drum heads or the like. It will be understood, however, that the method involved and the general structure used is readily adapted for use in connection with any sound propagating diaphragm and that changes and modifications of the present method or structure 45 to adapt the same for other types of musical instruments is within the scope of the present invention.

The structure involved in the present in-

vention includes an outer ring 10, which may be arranged for securement in association with any desired supporting structure or musical instrument.

In the completed structure as illustrated 55 in Figs. 1, 3 and 4, the diaphragm indicated at 12, is received within the ring 10, its side edges 13 being disposed parallel with the side walls of the ring 10 against the inner face of the side walls of the ring. A securing member 14 is provided between which and the ring 10, the edges 13 of the diaphragm are secured, the upper edge 15 of the ring being crimped inwardly to secure 60 the diaphragm and the upper edge of the member 14, locking the three portions securely together.

For assisting in securing the member 14 in the position illustrated, the lower edge 16 of the ring 10 is also bent inwardly to engage the lower edge of the member 14, whereby the member is securely locked between the edges 15 and 16.

With the present construction, it will readily be seen that snares may be secured beneath 75 the diaphragm 12. Referring more particularly to Fig. 4, it will be seen that the snares 17 extend across the diaphragm and over the upper edge of the securing member 14 and pass between the member 14 and the edges 13 of the diaphragm, to be secured by the crimping action of the upper edge 15 of the ring 10.

In the construction of the present invention it will be understood that the invention 80 is not confined to any specific materials. In practice, the ring 10 has been formed of a readily bendable metal and the diaphragm is preferably formed of any suitable semi-flexible material, such as paper, cloth, skin or the like. In practice it has also been found practical to use cardboard or some stiff material for the member 14.

Throughout the device it is obvious that 85 any desired materials may be used and that such materials are within the discretion of the manufacturer and form no part of the present invention.

In forming the present invention, the ring 10, as shown in Fig. 2, is provided with inwardly and downwardly extending edges 15

and 16. The diaphragm is cut and inserted within the ring 10, its side edges 13 lying parallel and against the inner face of the ring 10. The member 14 is then inserted within 5 the ring 10 and pushed upwardly to force the desired portion of the diaphragm between the ring 10 and the downwardly extending flange 15. When it is desired to use snares the same are placed beneath the diaphragm before 10 the member 14 is inserted and thus are secured with the diaphragm 12. After the insertion of the member 14, to provide proper tensioning of the diaphragm 12 and to lock the elements 14 and 12 securely together with 15 respect to the ring 10, the edges 15 and 16 are finely crimped, thus providing the finished device as illustrated in Fig. 1.

From the foregoing it will readily be seen that the present invention provides a structural method of novel and improved characteristics and which is readily designed to conform with the demands of economic manufacture.

It will be understood that numerous 25 changes and modifications and the full use of equivalents in the structure and method involved do not constitute departures from the spirit or scope of the appended claim.

What is claimed is:

30 A device of the character described, including a ring having inwardly disposed edge portions, a diaphragm having side portions disposed against the inner face of said ring, snares underlying said diaphragm with their 35 ends at the inner surfaces of the side portions of the diaphragm, means for securing said diaphragm and snares, said means including an annular member secured to said ring by said edge portions and securing said 40 diaphragm and snares between itself and said ring.
